UNITED STATES PATENT OFFICE.

CHARLES E. CLARKE, GEORGE HADLEY, AND JOHN C. CLIFFORD, OF BUFFALO, NEW YORK

IMPROVED MODE OF PRESERVING WOOD.

Specification forming part of Letters Patent No. 67,104, dated July 23, 1867.

To all whom it may concern :

Be it known that we, CHARLES E. CLARKE, GEORGE HADLEY, and JOHN C. CLIFFORD, of the city of Buffalo, in the county of Erie and State of New York, have invented a new and useful Process of Saturating Wood with any Preservative Liquid, or with any solid which can be brought by heat or solution to the liquid form, whether the purpose of the saturation be to preserve the wood from decay or for any other useful object whatever; and we do hereby declare that the following is a full, clear, and exact description of the same, reference being had to the accompanying drawings, forming part of this specification, in which we have represented an apparatus, partly in section and partly in elevation, which is adapted for performing our process.

The nature of our invention consists in saturating wood with vapor previously to saturating it with any suitable oleaginous or preservative material, and then by using the said oleaginous or preservative material as a condenser, causing a thorough saturation of the wood with such material.

To more plainly state our process, we will refer to it as consisting of two parts or stages.

In the first the wood, which may be used either dry and seasoned or green and water-soaked, is filled with an atmosphere of some kind of vapor. This is best effected by heating it in a suitable vessel, out of contact of air, in a gentle current of vapor, such as steam. The air and water which fill its tissues are expelled and carried off, and their place filled by the vapor employed for expelling them.

In the second part of our process the wood, while in the above-mentioned condition, and still hot, is immersed in the saturating liquid. Here it is allowed to remain until, by cooling, the vapor condenses, and the immersing liquid consequently enters and fills the vacuum cells or tissues which were previously occupied and filled by the vapor in the gaseous form.

By the first part of the process the wood is filled with condensable vapor; by the second, the vapor is condensed, and the room in the cells or tissues thus afforded by the vapor occupying a smaller space is occupied by the preserving or saturating liquid.

For the first part of the process we prefer the use of steam or superheated steam, but we may employ with equal efficiency the vapor of any substance whatever which has the proper degree of volatility.

For the second part of the process the liquid employed may be vegetable or animal fats and oils, gas-tar, gas-tar distillates, gas-tar cement, petroleum, petroleum-distillates, paraffine, asphaltum, rosin or other resinous bodies, varnishes; saline solutions, such as corrosive sublimate, chloride of zinc, sulphate of iron, and other analogous or known substances used for the purposes of impregnating wood; carbolic acid; coloring matters may also be employed; or, in short, any useful known liquid, or any useful known solid, or mixtures of solids and liquids, which can be brought to the fluid state may be used.

To perform our process, we place the pieces of wood *a a a* in the vessel *A*, and into the vessel *A* we introduce wet steam, either common or superheated, by means of the pipe *b*, leading from the steam-boiler *B*. We continue the flow or circulation of steam through the vessel *A*, amid the wood, as indicated by the arrows, for such a length of time as will insure a thorough saturation of the wood with the condensable vapor. The waste steam escapes at *c*.

One action of the steam or vapor upon the wood is to soften the resinous and fermentable matters contained in the wood. Another action is to expand the wood, open its pores, and expel the air contained in the pores or tissues.

After the wood is thus treated, the steam is shut off, and while the vapor is uncondensed in the pores or tissues, we flow into the vessel *A*, from a tank, *D*, by means of the pipe *c*, any oleaginous or preserving material. The quantity flowed into the vessel *A* should be sufficient to entirely immerse the pieces of wood which have been saturated with the vapor or steam. The oleaginous, saline, or other useful material used being cold or comparatively cool with respect to the temperature of the vapor first used, a rapid condensation of the vapors takes place within the cells or tissues of the wood, and these cells, which but a moment before were filled with the expanded

gas or vapor, become suddenly filled with the oleaginous substances or preserving materials, which constitute or form the bath of immersion.

To insure a perfect saturation of the wood with the preserving material, we allow the soaking process to go on for some hours, say from four to twelve hours, according to the thickness and nature of the material to be saturated.

The principle of our invention is a very plain and simple one, to wit: The vapor or steam heats and expands the wood, softens and displaces, or disperses, all resinous or sappy substances, and also expels the air in the cells. This done, it is obvious that when the steam is condensed, the spaces or cells in the wood which it occupied will no longer be filled to their capacity, and as this condensation takes place so soon as the wood becomes immersed by the oleaginous, saline, or other material, there is an immediate influx into these cells of the bath-preserving material.

Our main discovery is to use a hot condensable vapor to prepare the way for a cool, solid, condensing fluid, such fluid being the preserving or protecting material for the wood. As a given quantity of vapor occupies a space far greater than that which the condensed fluid of the same occupies, it naturally follows that space for the influx of the preserving or protecting material is provided at the moment this vapor is condensed by the influx of the preserving or protecting materials into the vessel.

When the wood is thoroughly saturated it is removed from the bath of immersion. The preserving or protecting material is then pumped up, for reuse, out of the vessel A into the tank by means of the apparatus E, and a fresh supply of wood, to be first steamed and then immersed in the preserving materials, is introduced into the vessel A, when the operation of steaming and immersing takes place in the order before described.

This same process may be usefully employed in the saturation of woods with coloring matters for the purpose of making imitations of the handsome natural woods used in the manufacture of costly furniture.

Wood treated by our process may be employed with great advantage for cabinet-work, interior wood-work of dwellings, ties for railroads, sills for bridges, and for a multitude of purposes, useful and ornamental, as well as for those founded solely on its freedom from speedy decay.

The form of the apparatus employed, or its particular construction, is not very material, any further than that it must fulfill the essential conditions of first saturating the wood with vapor as a means of afterward filling it with the requisite preserving and protecting substances.

When superheated steam is employed, a boiler for generating the steam, a superheater for raising the temperature of the steam above 212° F., and a vessel or chamber for holding the wood will all, if not absolutely necessary, be found convenient and serviceable.

A single boiler or still, with a suitable condenser attached, may be employed both for generating the vapor and for holding the wood under treatment, if so constructed as to be kept filled with a continuously renewed atmosphere of the vapor in the first part of the process, and to receive the infiltrating liquid in the second.

What we claim as our invention, and desire to secure by Letters Patent, is—

The within-described process of treating wood for the purpose of preserving, protecting, solidifying, or coloring the same.

CHARLES E. CLARKE.
GEORGE HADLEY.
